UNITED STATES PATENT OFFICE.

EDWARD E. FLEMING, OF WASHINGTON COUNTY, MARYLAND.

ENVELOP-STAMPING MACHINE.

No. 807,114.

Specification of Letters Patent.

Patented Dec. 12, 1905.

Application filed August 17, 1904. Serial No. 221,055.

To all whom it may concern:

Be it known that I, EDWARD E. FLEMING, a citizen of the United States, residing in the county of Washington and State of Maryland, 5 (whose post-office address is Mason and Dixon, Pennsylvania,) have invented certain new and useful Improvements in Envelop-Stamping Machines; and I do hereby declare the following to be a full, clear, and exact description of the invention, such as will enable others skilled in the art to which it appertains to make and use the same.

This invention relates to machines for affixing postage-stamps on envelopes or packages, particularly to machines which detach and apply the stamps from sheets as issued by the Government and which have a holder for the sheet or sheets of stamps and a carriage or slide carrying an envelop - support and suitable 20 stamp detaching and affixing devices adapted to be moved successively into position for utilizing one stamp after another. A modern example of such a machine is illustrated, described, and claimed in my former patent, No. 25 767,269, dated August 9, 1904. Said machine as therein illustrated comprises, chiefly, a stamp-box for holding a sheet or sheets of stamps having a slot or opening at one end to permit the stamps to pass out; coacting rollers for feeding out a sheet of stamps, which sheet is fed out and utilized one row at a time; a carriage or slide carrying an envelop support, moistener, and cutter and plunger for detaching and affixing a stamp on the envelop 30 or package, said carriage being movable to bring the stamps of each row successively within range of the envelop-support and cutter and plunger.

My present invention, which is generally 40 applicable to machines of this character, provides the following improvements: First, the carriage is spring-impelled to travel step by step across the machine by simple, compact, and efficient spring mechanism and accessory 45 devices, including a pawl or catch for holding the carriage adapted to be released by the operator's finger to permit movement one step at a time; second, the stamp-box is detachable, and it is supported conveniently and firmly 50 without the use of movable fastenings and without a supporting-frame, by which the machine is rendered simpler and more compact; third, means is introduced for holding the last 55 row of stamps of a sheet in proper position on the slide or carriage, and also means for hold-

ing the stamps firmly or steadily during the operation of detaching and affixing a stamp; fourth, in addition to the usual moistener for dampening the gum on the stamps means is also provided for moistening the gummed flaps 60 of the envelop, while certain minor features of improvement are introduced, as hereinafter appearing.

In the accompanying drawings, which form a part of this specification, I have illustrated 65 an envelop - stamping machine substantially similar to my aforesaid patented machine with my new improvements embodied therein.

A brief general description of the illustrated machine will first be given, using the same reference-letters employed in the aforesaid patent to indicate corresponding parts, after which my new improvements will be fully set forth, designating novel features by numerals, and the invention will then be defined in the annexed claims.

Figure 1 is a perspective view of the machine. Fig. 2 is a cross-section thereof. Fig. 3 is an enlarged fragmentary section. Fig. 4 is a detail longitudinal section of the rod F 80 and spring mechanism. Fig. 5 is a detail view of the winding-drum to which the cord from the slide or carriage is connected, showing its inner ratchet. Fig. 6 shows a fragment of one end of the machine, showing the slide or carriage and the winding-drum.

The letter A designates the base of the machine; B B, standards rising therefrom; C C, arms extending from said standards to support the mechanism between them.

D denotes the inclined stamp-box, and E its removable cover, the lower end of the stamp-box being open to allow a sheet of stamps to pass out. In Fig. 3, d is a strip hinged at d' at the lower front of the stamp-box and turned 95 back down upon the lower edges of the sheets of stamps to prevent the several sheets from sliding down or out, only the uppermost sheet being allowed to pass over said strip d.

The letter e denotes a flap on the under side 100 of the cover E to rest upon the sheet of stamps fed out and hold it steady.

F and G denote longitudinal rods connecting the standards or supports at opposite sides of the machine. H and I are similarly-disposed rods or bars, also connecting said supports and forming supporting-guides for the carriage or slide K.

J J are coacting feed-rollers for feeding out the sheet of stamps onto slide K. The sheet 110

is fed so as to bring its lowermost row onto said slide.

5 L is a perforated removable cover to hold the row of stamps on the slide K and yet enable the stamps to be seen by the operator.

10 M is the casing for the stamp detaching and affixing device, such as a cutter and plunger (not shown) operated by the plunger-rod P. This casing is mounted on the slide or carriage (here at the left-hand end) over a square hole or opening of sufficient size to permit a stamp as it is detached from its sheet to be pressed by the plunger upon the envelop or package. V is a combined water-tank and 15 envelop-support carried by the slide below the said opening. X is a moistening-roller resting in a slot or opening in said support and carried by a lever whose projecting front end is raised by the envelop as the envelop is raised by the envelop, so as to lift the roller which wipes over the corner of the envelop and moistens it to cause the stamp to adhere thereto.

20 The description thus far given answers also 25 to the machine disclosed in my aforesaid patent except that the supporting-frame for the stamp-box (shown in said patent) is dispensed with and improved means is substituted for holding the stamp - box, as hereinafter explained.

25 In operation the sheet of stamps is 30 fed by rollers J so as to bring the lowermost row of stamps onto the slide K. The slide is then moved a step, to the right in this instance, to bring the cutter and plunger over 35 the first stamp of the row. The envelop to be stamped is pushed back on the envelop-support V, thus lifting the moistening-roller X out of the tank and causing it to wipe over the corner-surface of the envelop. Then the

40 operator pushes down on the plunger P, thereby severing the stamp and pressing it upon the envelop. The slide is now moved another step to the right to bring the cutter and plunger over the second stamp, whereupon the 45 same operation is repeated, or the second stamp is applied either to the same or another envelop. When all the stamps of the first row have been utilized, the operator pushes the slide or carriage to the left again and feeds 50 the sheet so as to bring the second row of stamps onto the slide. Then the same series of successive operations is repeated, and so on until the whole sheet is used.

55 My new improvements will now be described 55 without limiting myself to the specific details of construction and arrangement shown, since the improvements are susceptible of other embodiments and various modifications.

60 The slide or carriage K is connected by a 60 cord or flexible connection 1 to a spring-actuated drum 2, adapted under tension of its spring to wind up the cord in feeding the carriage step by step in one direction—in this case from left to right—and to let out said cord 65 while winding up the spring as the carriage

is moved back to the left again or in position to begin utilization of a new row of stamps. The cord 1 is shown connected to the bottom of the carriage at the left and passing around little guide-pulleys 3 and 4 at the right of the 70 machine.

75 The carriage-spring 5, Fig. 4, is contained within the rod F, which is hollow or tubular for that purpose. It is a coiled torsional spring encircling an inner rod 6 and has one end connected, as at 7, to a standard B and its other end connected, as at 8, to said rod 6. The rod 6 is connected to the drum 2, so that when the carriage is moved to the left the drum as it is turned by the cord will turn said 80 rod, and thus wind up the spring, while the force of the spring will reverse the turn of the rod and drum for winding up the cord, and thus pulling the carriage in the opposite direction.

85 In order to provide for adjusting the spring or increasing its tension, the rod 6 is connected to the drum 2 by a suitable ratchet device—such, for example, as shown in Figs. 4 and 5, wherein 9 denotes a disk on the rod, 10 a 90 spring-pressed dog carried thereby, and 11 an internal ratchet in the drum engaged by said dog. It is obvious that when the drum is turned by the cord in pulling the carriage to the left the rod will be turned, by reason of 95 the dog engaged by a ratchet-tooth, so as to wind the spring, while the reverse turn of the rod under force of the spring will turn the drum through the same connection. The rod, however, may be turned independently in a 100 direction for winding the spring, and thus increasing the tension, for which purpose a handle or finger-piece 12 is provided on the rod at the outer side of the drum.

105 For the purpose of feeding the carriage step by step only with proper movements for bringing the cutter and plunger over one stamp at a time a dog or catch 13 is shown pivoted at the left of the carriage adapted to engage notches 14 in the guideways I, said notches 110 being spaced at distances corresponding to the widths of the stamps. Said dog has at the opposite side of its pivot a finger-piece or presser 15, with a tailpiece 16 to limit downward movement of the presser. The operator simply presses upon the presser 15 to release the dog or catch, and thus permit the carriage to move by force of its spring one 115 step to the right, movement being limited by the dog or catch 13 engaging in the next 120 notch 14.

125 Number 17 denotes a spring bearing on the dog or catch to keep it down on and insure its engagement in the notches 14. The dog 13 is shown carrying also an arm 18, which bears upon the left - hand end of the perforated cover L and holds it pressed upon the stamps beneath it when the carriage is at rest, so that the stamp to be detached and applied to the envelop is held steady; but 130

when the dog or catch is raised from a notch to permit the carriage to move a step to the right the arm 18 is also raised therewith, thus releasing the row of stamps from under the cover L and permitting the slide and cover to move onward while the stamps remain stationary. The cover L is of light sheet metal and rests very lightly upon the row of stamps, except when pressed upon by the arm 18.

10 The opposite end of said cover is fastened to the slide, as by the set-screw 19.

In using the machine it is understood that the sheet of stamps is fed out from the stamp-box by rollers J so as to cause the lowermost row to enter between the top of slide K and the plate or cover L, the front rib or shoulder k of the slide forming a stop for the front edge of the row of stamps. Now as the slide or carriage is moved step by step to bring the cutter and plunger successively over the stamps the row is held in proper position by the portion of the sheet within the stamp-box or gripped between the rollers J; but when the last row is fed onto the slide there is no such means for retaining it and there is liability of the stamps jarring out of position or away from the longitudinal shoulder k. To obviate this liability, a longitudinal strip or plate 20 is shown vertically disposed between 20 the back of the slide and the feed-rollers and connected to a lever 21. Ordinarily the plate is depressed, so that the stamps can be fed over it from the feed-rollers; but when the last row of stamps is on the slide the operator can move the lever 21 to raise the plate 20, which will thus confine said row of stamps between it and shoulder k. By means of a teat 22 on standard B, adapted to engage a dent in lever 21, the said lever may be held in position to keep plate 20 raised when desired. Plate 20 is shown having a pivotal connection 23 to lever 21, by means of which it is upheld.

The stamp-box D is supported by rods F and G by means of curved fingers or projections 24 and 25 on the bottom of the stamp-box, which take under said rods when the stamp-box is placed thereon and hold the box firmly to the rods. The stamp-box is supported between projections or shoulders 26 on rod 50 F, which insure placing it in proper relation to the slide or carriage. Thus the box is simply but firmly supported and is readily detachable.

The envelop-support and water-tank V have 55 an auxiliary tank with a moistening-roller 27 therein whose upper surface is uncovered by an opening in the tank. A thin strip or spring 28 on the tank presses on the upper surface of the roller. The gummed flap of an envelop 60 may be moistened for sealing by passing it over this roller under the finger 28, which presses it against the roller. The moistening-roller X is shown parallel with the slide K, so that it lifts and wipes over the surface of the 65 envelop when pushed back on the envelop-sup-

port. The roller 27 is at right angles to roller X and is contained in a part of the tank projecting in front of the main tank or envelop-support, which thus provides a very convenient means for moistening the envelop-flap. 70

I claim as my invention and desire to secure by Letters Patent of the United States—

1. An envelop-stamping machine having, in combination, a frame comprising a holder for a sheet of stamps, and guideways for a carriage along the front of said holder, a carriage supported by said guideways and carrying a stamp detaching and affixing device and adapted to move step by step for bringing said device successively in range of the stamps of a row, a drum having a flexible connection with said carriage, an actuating-spring for said drum adapted to be wound thereby when the carriage is moved from an advanced position back to initial position and then to exert its force 80 in reversing the drum to wind the flexible connection and thus impel the carriage step by step in an opposite direction, notches at intervals in one of said guideways spaced according to the widths of the stamps, and a spring-catch pivoted to the carriage and adapted to engage said notches to hold the carriage stationary at its successive positions and having a finger-piece for disengaging said catch from said notches to permit the movement of 95 the carriage.

2. An envelop-stamping machine having, in combination, standards and guideways for a carriage connecting them, a stamp-box supported between said standards, a carriage traveling on said guideways carrying a stamp detaching and affixing device, a hollow tube connecting said standards, a rod therein, a torsional spring encircling said rod within said tube having one end connected to a standard 100 and the other end connected to the rod, a drum on said rod having a flexible connection with said carriage, and a catch for holding the carriage in successive positions for operation of the stamp detaching and affixing device on 105 successive stamps.

3. In an envelop-stamping machine, means for holding a sheet of stamps, a slide or carriage onto which a row of stamps is presented, a stamp detaching and affixing device carried by the carriage adapted to be brought within range of the stamps in succession, a top plate or cover on the carriage above the row of stamps, a spring for impelling the carriage, a catch for holding the carriage in its successive 110 operative positions, and a presser carried by said catch adapted to press upon said top plate when the carriage is at rest and to lift away therefrom when the catch is released to permit movement of the carriage. 115

4. In an envelop-stamping machine, the combination with means for holding a sheet of stamps, of a slide carrying a stamp detaching and affixing device, means for feeding the sheet to place a row of stamps on said slide, 120 125 130

and a movable plate adapted to lift behind the slide to retain the last row of stamps thereon.

5. In an envelop-stamping machine, stands and longitudinally-disposed connecting-
5 rods, and a removable inclined stamp-box supported by said rods and having curved bottom fingers taking under said rods to hold the stamp-box firmly in place.
- 10 6. An envelop-stamping machine having, in combination, an inclined stamp-box open at its lower edge to permit feeding out a row of stamps from a sheet in the box, a stamp detaching and affixing device, and a carriage
15 therefor adapted to move said device step by step along said edge of the box to engage the stamps of the out-fed row in succession, a spring impelling said carriage in one direction and adapted to be wound by the shifting
20 back of the carriage, and a spring-pressed catch pivoted to the carriage and adapted to engage a series of notches along the path of movement and having a finger-piece for releasing it.
- 25 7. In an envelop-stamping machine, a stamp sheet holder, a stamp detaching and applying device, a carriage, and carriage-actuating mechanism comprising a rod having a torsional spring adapted to turn it in one direc-
30 tion, a drum on said rod and an intermediate ratchet adapted to turn the drum with the

rod in one direction and the rod with the drum in the opposite direction but to permit independent turning of the rod in the latter direction to adjust the tension of the spring, means 35 for turning said rod independently to effect such adjustment, and connections between said drum and the carriage.

8. In an envelop-stamping machine, means for holding a sheet of stamps, a slide or carriage onto which a row of stamps is presented, a stamp detaching and affixing device carried by the carriage adapted to be brought within range of the stamps in succession, a top plate or cover on the carriage adapted to rest upon 45 the top of said row of stamps, and a spring-actuated presser adapted to press upon said top plate and having means for releasing it when the carriage is moved.

9. In an envelop-stamping machine, a frame 50 having guideways for the carriage of a stamp-affixing device and longitudinally-disposed rods, and an inclined stamp-box removably supported in proper relation to the carriage upon said rods and having curved bottom fin- 55 gers taking under said rods.

In testimony whereof I affix my signature in presence of two witnesses.

EDWARD E. FLEMING.
